AUTOMATIC DOOR-OPERATING MECHANISM.

Application filed December 6, 1923. Serial No. 679,013.

To all whom it may concern:

Be it known that we, BENJAMIN RATCLIFFE ADKINS and WILLIAM YORATH LEWIS, both subjects of the King of England, and 5 residing, respectively, at Upper Warlingham, Surrey, in England, and Southend-on-Sea, Essex, in England, have invented certain new and useful Improvements in Automatic Door-Operating Mechanism, of 10 which the following is a specification.

This invention relates to mechanism for operating vehicle doors or gates automatically, and is more particularly intended for use on passenger vehicles such as railway 15 carriages or lifts, although generally applicable to all vehicles movable along fixed tracks.

The primary object of the invention is to provide a door or gate for such a vehicle, which will automatically open or close 20 when required, as for example in the case of a railway carriage door when the train enters or leaves a station. A further object is to avoid risk of accidents which 25 may occur as the result of the forced closing of a positively actuated automatic door.

In the automatic door-operating mechanism according to the present invention a door or gate is adapted to be opened or 30 closed by means of a lever mechanism, which is operated by the engagement of a roller with the surface of a fixed ramp or cam track, past which the vehicle moves. The ramp or cam is preferably disposed on 35 that side of the vehicle track which is remote from the doors to be operated. In this case the roller is conveniently carried on an arm mounted on a shaft, which is disposed transversely across the vehicle and by 40 rotation of which the lever mechanism is operated.

The length of the operative surface of 45 the cam track or ramp is preferably such that the door or gate is positively moved thereby only for a portion of its travel, the remaining motion of the door taking place under the action of gravity or of a spring, which may in some instances be employed with advantage. For this purpose the door 50 or gate may be pivoted about a horizontal axis or may be supported on one or more horizontally pivoted arms, on which the lever mechanism acts.

The invention may be carried into practice in various ways and two preferred con- 55

structions for use with railway carriage doors or gates are illustrated by way of example in the accompanying drawings, in which—

Figure 1 is a side elevation of a railway 60 carriage showing one construction,

Figure 2 is an end elevation, partly in section on the line 2—2 of Figure 1,

Figure 3 is a diagrammatic view showing the cam tracks for opening and closing the 65 doors, and

Figure 4 shows another construction in side elevation.

In the construction shown in Figures 1 and 2 the gate consists of two bars A A' 70 rotatably mounted on horizontal pivot pins A' carried respectively on lugs B' projecting from the door posts B, the inner ends of the bars A resting (when the gate is closed) on shoulders C' on a central supporting post 75 C. Rigidly connected to each gate bar A on the other side of its pivot pin A' is a short lever arm A², which is connected by means of a link D to one arm E of a two-armed lever pivoted at E' near the bottom of the 80 carriage frame. The other arm E² of this lever is connected by means of a rod F to the corresponding arm E² of the two-armed lever on the other side of the doorway, this connecting rod F being disposed below the 85 floor of the carriage. At a point G' intermediate in its length the connecting rod F has pivoted to it a third lever arm G mounted on a shaft H lying transversely across the vehicle. The shaft H is in line with the 90 two pivots E' E' of the two-armed levers and the three lever arms E² E² G to which the rod F is connected are all of the same length, so that the rod can only move parallel to itself. At its far end on the other 95 side of the carriage the shaft H has mounted on it an arm J' carrying a small roller J. This roller J projects from the carriage in such a position as to engage a fixed cam track K' or K² disposed adjacent to the 100 main track.

Thus when the roller J engages the cam track the shaft H is rotated causing the lever arm G at its other end to rock and move the connecting rod F. This in its turn 105 rocks the two-armed levers E E² about their pivots E', and their motion is transmitted through the links D to the short lever arms A² connected to the gate bars A, thus effecting the opening or the closing of the gate. 110

The surface of the cam track, with which the roller J engages, is shaped according to the requirements of the railway system, so that it slopes in one direction, say an up-slope as shown at K' in Figure 3, when it is required to open the gate and in the other direction—a down-slope K²—when the gate is to be closed. In the case of the down-slope K² it is necessary that the roller 10 J should engage on the underside of the surface, in order that it should be positively actuated thereby.

The length of each operative down-slope K² of the cam track is made insufficient completely to effect the closing of the gate, so that the gate is positively actuated only for a portion of its travel. After the gate has thus been partially closed, it completes its course under its own weight or by the assistance of a spring if required. A counter-weight L or spring may also be provided in a convenient position (as shown on an arm L' integral with the arm J') to balance the weight of the levers, links, and other moving parts of the mechanism so that the gate or door does not come to rest in its closed position too violently. This arrangement prevents the risk of serious injury for example to a passenger who is still in the doorway when the gate is being closed. A similar arrangement may also be provided for the opening of the gate if desired, the length of each up-slope K' of the cam track being made shorter than is required completely to effect the opening of the gate. The balance of the moving parts and prevention of the gate from coming too violently to rest in its opened position may similarly be effected by the employment of a counter-weight or spring, which may in some instances, as in the case illustrated, be the same one L used for the closing operation, thus serving both purposes.

Other forms of gate or door may be employed, if desired. Thus, for example, if it is required completely to close the doorway, two doors may be employed, each door being pivotally supported on one or more horizontally pivoted supporting arms. This arrangement is shown in Figure 4, in which each door M is carried on two parallel arms N O of equal length, one of these arms N being actuated in a manner similar to that already described for the gate bars A in the construction shown in Figures 1-3, whilst the other arm O is pivoted to the frame of the carriage at a convenient point O'. The arms N are pivoted at N' near the floor of the carriage and have lever arms N² rigidly connected to them. These arms N² are connected by means of rods P to two of the arms Q Q' of a three armed lever pivoted at Q². The third arm Q³ of this lever carries a roller R which engages with the cam track S. In this construction it will be no-

side of the main vehicle track as the doors of the carriage, but if desired the cam track may be disposed on the other side. In this case the lever Q Q' would be mounted on a shaft passing across the vehicle and carrying a roller arm at its far end, as in the construction shown in Figures 1-3.

Thus when the roller R engages an up-slope of the cam track S, the lever Q Q' Q³ 75 will be rocked about its pivot Q² and will act through the rods P to move the arms N about their pivots. Owing to the fact that the two arms N and O for each door are parallel to one another and are of the same 80 length, they will act as a parallelogram linkage when the roller R engages the cam track S, and each door will move parallel to itself about the two pivots N' and O'. As in the previous construction, the cam track S is 85 provided with a down-slope, on the lower surface of which the roller R engages to close the doors, and the sloping parts of the cam track are of a length insufficient completely 90 to effect the opening or closing of the doors, the last portion of the travel of the doors being effected under their own weight.

The invention has been described primarily with reference to double gates or doors closing from the sides of the doorway 95 towards the centre, but single doors or gates may be employed if desired. Moreover it is not necessary to the invention that the doors should be pivoted about horizontal axes. Thus for example sliding doors or gates may 100 be employed.

A separate roller may be provided for the operation of each door or gate, or alternatively a single roller may be employed to actuate a number of doors simultaneously.

It will be understood that the particular arrangements described have been given by way of example only and that considerable modifications may be made in the constructional details without departing from the 110 spirit of the invention. Thus for example the cam track may lie wholly in a horizontal plane and may slope towards the left or right to effect opening and closing.

What we claim as our invention and desire 115 to secure by Letters Patent is:—

1. In automatic door-operating mechanism for use in vehicles movable along fixed tracks, the combination of a door mounted to swing about a horizontal pivot, a lever mechanism adapted to move the door about its pivot, a roller operatively connected to such mechanism, and a fixed cam track having two operative portions sloping in opposite directions, the roller being adapted to engage with the surface of one operative portion to effect the opening of the door and with the surface of the other operative portion to effect the closing of the door, the length of each operative portion being such 120 125 130

only for a portion of its travel in either direction as set forth.

2. In automatic door-operating mechanism for use in vehicles movable along fixed tracks, the combination of a plurality of doors mounted to swing about horizontal pivots, a lever mechanism adapted to operate each door, a shaft which is disposed transversely across the vehicle and by rotation of which the lever mechanisms are actuated, an arm mounted on the end of the shaft remote from the doors to be operated, a roller carried by this arm, and a fixed cam track past which the vehicle moves and with the surface of which the roller engages in such a manner as to rock the shaft and thereby to operate the doors, the length of an operative portion of the surface of the cam track being such that the doors are positively moved thereby only for a portion of their travel as set forth.

3. In automatic door-operating mecha-

tracks, the combination of a plurality of 25 horizontally pivoted arms, a door mounted thereon so as to be movable about the horizontal pivots, a lever mechanism adapted to move the door about its pivots, a roller operatively connected to such mechanism, and 30 a fixed cam track having two operative portions sloping in opposite directions, the roller being adapted to engage with the surface of one operative portion to effect the opening of the door and with the surface 35 of the other operative portion to effect the closing of the door, the length of each operative portion being such that the door is positively moved thereby only for a portion 40 of its travel in either direction, the remaining motion of the door taking place under the action of gravity as set forth.

In testimony whereof we have signed our names to this specification.

BENJAMIN RATCLIFFE ADKINS.

WILLIAM YORATH LEWIS.
